(57) **CLAIM**

The ornamental design for a display screen or portion thereof with a transitional graphical user interface as shown and described.

DESCRIPTION

FIG. 1 is a front perspective view of a handheld computing device with a display screen or portion thereof with a transitional graphical user interface showing a first image in a sequence according to the new design; FIG. 2 is a front view thereof;

FIG. 3 is a front view of a second image thereof;

FIG. 4 is a front view of a third image thereof;

FIG. 5 is a front view of a fourth image thereof;

FIG. 6 is a front view of a fifth image thereof;

FIG. 7 is a front view of a sixth image thereof;

FIG. 8 is a front view of a seventh image thereof;

FIG. 9 is a front view of an eighth image thereof;

FIG. 10 is a front view of a ninth image thereof;

FIG. 11 is a front view of a tenth image thereof;

FIG. 12 is a front view of an eleventh image thereof;

FIG. 13 is a front view of a twelfth image thereof;

FIG. 14 is a front view of a thirteenth image thereof;

FIG. 15 is a front view of a fourteenth image thereof; and,

FIG. 16 is a front view of a fifteenth image thereof.

The design sequentially transitions between the images shown in FIGS. 2–16. The process or period in which one image transitions to another image forms no part of the claimed design.

Broken lines in FIGS. 1–16 show portions of a computing device with the display screen or portion thereof and form no part of the claimed design.
